ROOM AIR CONDITIONER FRONT PANEL

Wallace H. Appel and Clarence F. Graser, Columbus, Ohio, assignors to Westinghouse Electric Corporation, a corporation of Pennsylvania

Filed Sept. 15, 1969, Ser. No. 19,151

Term of patent 14 years

Int. Cl. D23—04

U.S. Cl. D23—141

FIG. 1 is a front perspective view of a room air conditioner front panel embodying our new design;

FIG. 2 is a vertical sectional view taken along line II—II of FIG. 1; and

FIG. 3 is a front view, enlarged relative to FIG. 1, of a fragmentary portion of the lower grill shown in FIG. 1 to illustrate the woven grass effect of the front grill.

The stippled area of FIG. 1 indicates a dark shade of that area.

I claim:

The ornamental design for a room air conditioner front panel, substantially as shown and described.
